UNITED STATES PATENT OFFICE.

ARBA ARDON PROFFITT, OF CHICAGO, ILLINOIS, ASSIGNOR TO WESTERN ELECTRIC COMPANY, INCORPORATED, OF NEW YORK, N. Y., A CORPORATION OF NEW YORK.

TOOL.

Application filed July 20, 1927. Serial No. 207,069.

This invention relates to tools, and particularly to guarded awls for use in connection with the handling of cable strands and the like.

5 The primary object of the invention is to provide a tool with a guard which will effectively shield the working portion of the tool without impairing the free and convenient manipulation thereof.

10 In accordance with the general features of the invention, one embodiment thereof consists in a strand working tool or awl which includes a shank secured at one extremity to a handle, the opposite end thereof being pointed and slightly curved for use with cable strands. A resilient guard carried by the shank serves to normally shield the pointed end thereof and is designed to deflect when pressed against a cable, thereby permitting 15 the free and convenient use of the awl.

The objects of the invention will be more apparent from the following detailed description taken in connection with the accompanying drawing, wherein

20 Fig. 1 is a perspective view of a guarded cable awl representing one embodiment of the invention, said awl being shown in operative association with a cable;

Fig. 2 is an enlarged fragmentary view of 25 the working portion of the awl and associated guard, the guard being shown in its normal tool shielding position, and

Fig. 3 is a fragmentary elevational view 30 similar to Fig. 2 disclosing the resilient guard in a deflected position to permit the free manipulation of the working portion of the tool.

Referring now to the drawings wherein like numerals have been employed to designate similar parts throughout the various 40 figures, it will be observed in Fig. 1 that one embodiment of the invention consists in a cable or strand working tool denoted generally by the numeral 10. This tool 10 comprises a tool shank 11 secured at one end to a suitable manipulating handle 12, the opposite or working end of the shank 11 being slightly curved and formed so as to present a pointed working tip 14. The design of the working portion of the shank 11 is such as to peculiarly adapt it for extensive use in connection 45 with the manipulation of individual strands of a cable 15 as clearly disclosed in Fig. 1.

A resilient guard 16 of the tool 10 comprises a flexible strip 18 which is suitably secured at 50 one extremity at the junction of the shank 11

and the tool handle 12. The opposite or free extremity of the strip 18 is formed with a loop portion 19 having a slot 20 to permit companion portions of the loop 19 which form the sides of the slot 20 to be yieldingly maintained in a guarding or shielding relation with respect to the pointer tip 14 of the shank 11 as clearly shown in Figs. 1 and 2. It will be clear that when the guard 16 is in its normal position, the loop 19 thereof will serve to 60 effectively shield the tip 14, and in order to operatively associate the tip 14 with the strands of the cable 15 or to insert the tip between the cable and binding stitchings 21, it is only necessary to cause the deflection 65 of the guard 16. This deflection may be very readily produced by pressing the portions 19 against the outer surface of the cable 15 or other material with which the tool is associated, contemporaneously with the operative 70 association of the tip 14 with the individual strands. The loop 19 may be formed so as to present the proper curvature of the external or engaging surface thereof in accordance 75 with the particular type of tool with which it is to be employed in order to effect the proper deflection when the tool is operatively associated with the work.

In the operation of the tool 10 when used 80 in connection with cable strands, it is only necessary for the user to carry the shielded tip 14 into association with the outer surface of the cable 15 or the stitchings 21 as clearly 85 shown in Fig. 2. By pressing the tip of the guard 16 against the cable it is deflected away 90 from the tip 14 which is then in a position to be inserted between the individual cable strands or beneath the stitchings 21 as may be desired. In forming telephone switchboard cables it is sometimes necessary to insert an 95 additional cable strand after the stitchings 21 have been applied as shown in Fig. 1 to the cable 15. In order to accomplish this it is necessary to raise the individual stitchings to 100 permit the insertion therebeneath of the added cable strand. In such instances the user sometimes holds the tool 10 with the right hand by gripping the handle 12 and the left hand is gripped about the cable 15 immediately ahead of the point where the tool is 105 applied. In this manner the user's left hand serves to steady the cable and counteract the force occasioned by the advancement of the tip 14 into the cable strands beneath the stitching, and it will be obvious that when an 110

unguarded working tools employed in this manner, care must be exercised to prevent the pointed tip thereof from being carelessly advanced too far or too suddenly in order to prevent injury to the user's left hand. Having the tool equipped with the described guard, the hazards incident to such an operation are materially reduced and the infliction of injuries practically eliminated. It will 10 also be clear that the guard 16 which normally occupies a tool shielding position also serves to prevent injuries which often result from inherently dangerous tools which are permitted to lie promiscuously about a shop. 15 In such instances the guard 16 supplies a very effective means for preventing injury and likewise to prevent the guarded portion of the tool from being unnecessarily mutilated. By deflecting the resilient guard in the manner described the tool may be employed freely and safely.

Although the invention has herein been described in connection with a guarded tool or awl for handling strand material, obviously it is capable of many other applications and therefore the invention should be limited only by the scope of the appended claims.

What is claimed is:

1. A tool including a working element, and 30 a member for shielding the working element fixed at one portion thereto, said member being adapted to swing away from the working element upon engagement thereof with the work to which the tool is applied to permit the free use of the tool.

2. A tool including a working element, and 40 a member for completely shielding the working portion of the element fixed at one portion thereto, said shielding member being adapted to move laterally of the working element upon engagement thereof with the work to which the tool is applied to permit the free use of the tool.

3. A tool including a working element, and 45 a resilient member for shielding the working element, said member being resiliently held in normal shielding relation with respect to the working portion of the element, and adapted to deflect upon engagement thereof

with the work to which the tool is applied to 50 permit the free use of the tool.

4. A tool including a sharp working element, and a guard comprising a resilient member secured at one extremity to the working element and formed at the other extremity to shield the sharp portion of the working element and adapted to deflect from the sharp portion upon the association of the tool with the work to permit the free use of the tool. 55

5. A tool including a pointed working element, a resilient guard strip secured at one extremity to the working element, and a shielding member at the free extremity of the strip having an arcuate surface for engagement with the work with which the tool is associated to effect the proper deflection of the guard strip. 60

6. A strand working tool including a pointed element curved at the pointed end thereof, a handle supporting the opposite end of the element, and a resilient guard strip secured at one extremity to the junction of the pointed element and the handle, the free end of the strip being formed with a loop portion for shielding the pointed end of the working element. 70

7. A tool including a working element, and a member for shielding the working element operatively connected thereto, said member having a bifurcated portion between the furcations of which the working element normally is positioned and upon engagement of the bifurcated portion with the work to which the tool is applied the member moves to permit the free use of the tool. 80

8. A tool including a working element, and a member for shielding the working element resiliently connected thereto, said member at one extremity having a bifurcated portion extending laterally therefrom between the furcations of which the working element normally is positioned and upon engagement of the portion with the work to which the tool is applied the member yields to permit the free use of the tool. 90

In witness whereof, I hereunto subscribe my name this 8th day of July, A. D. 1927.

ARBA ARDON PROFFITT.
